UNITED STATES PATENT OFFICE.

RAY H. MANSON, OF ELYRIA, OHIO, ASSIGNOR TO THE GARFORD MANUFACTURING COMPANY, OF ELYRIA, OHIO, A CORPORATION OF OHIO.

AUTOMOBILE-HORN.

1,143,845.

Specification of Letters Patent.

Patented June 22, 1915.

Application filed June 7, 1912. Serial No. 702,183.

To all whom it may concern:

Be it known that I, RAY H. MANSON, a citizen of the United States, residing at Elyria, in the county of Lorain and State of Ohio, have invented certain new and useful Improvements in Automobile-Horns; and I do hereby declare the following to be a full, clear, and exact description of the invention, such as will enable others skilled in the art 10 to which it appertains to make and use the same.

My invention relates to signaling devices, and more particularly to devices of that character adapted to be used upon automobiles, motor boats and other vehicles, though of course, I do not wish to be limited to this use, since my invention applies to fog horns and signaling devices of a similar nature. So far as I am aware, the use of devices of 15 this kind, before I entered the field, was limited to a device adapted to produce a single signal. This signal is usually of a harsh objectionable tone, such as frequently angers the person warned, disturbs traffic 20 in the day and sleep by night. Some of the signal devices have been so objectionable that police ordinances have prohibited their use in certain jurisdictions. On the other hand, those which have produced only a low 25 tone have been objectionable for the reason that they fail to give the desired warning when there is an emergency, when it is desired to warn a person at a distance, or the driver of a noisy vehicle. In order to meet 30 these situations, many people have resorted to the employment of two horns, one giving a low note and the other giving a high note. This is objectionable for many reasons. In the first place, it is necessary for the driver 35 to use his mind in deciding which signal he wishes to employ and in selecting the controlling means for the operation of the particular signal. In order to do this, he must detract his attention from the driving of the 40 vehicle at a time when it is most required there, as the signals are employed in emergencies, when passing through a busy street or when turning out of the road to pass another vehicle, a maneuver which frequently 45 throws the machine into rough ground at the side of the road or adjacent to dangerous ditches, etc., where the steering is of the utmost importance. In the second place, it litters the already crowded 50 front of the car with apparatus which in-

creases the care and the expense of cleaning and maintaining the car. Moreover, it is expensive to provide two signaling devices.

One of the objects of my invention is to provide a single device which is capable of giving two signals—one loud in tone, suitable for warning people at a distance, in emergencies or in noisy surroundings, and second, a service signal which is low in note, but which is adequate to warn people in 60 urban districts or in crowded thoroughfares. This signal should be of a note which is not objectionable, but which is nevertheless loud enough to serve these purposes. By this I greatly reduce the expense not 65 only of providing the signals, but of maintaining the car accessories and of keeping them clean.

Another object of my invention is to provide means which may be operated without 70 detracting the attention from the operation of the vehicle, without the driver having to think which signal it is desired to operate, and without his having to move his hands from the steering wheel. To accomplish 75 this, I provide contiguous controlling devices for the horn, which devices control the production of the different signals.

I am aware that heretofore a single horn has been provided controlled by a plurality 80 of devices mounted upon different parts of the car, but these were incapable of being operated to produce different tones by the driver without his having to think which controlling device to operate to produce a 85 certain tone, or without his having to move his hand for the purpose of controlling the operation of the horn. I find it desirable to place these controlling devices so close together that they may be operated by the 90 thumb of the driver. In fact, it is preferable to place them so close together that both may be operated without moving the thumb except by rocking or further depressing it. For example, I may employ in 95 the electrically controlled devices a plurality of push buttons mounted contiguous to each other, as in the forms illustrated in the drawings.

Other objects of my invention and the 100 invention itself will be better understood from the detailed description of the forms illustrated.

Figure 1 is a section through a device 105 illustrating my invention, with which a dia-

gram of the circuit connections is illustrated. Fig. 2 illustrates one method of the association of the contiguous controlling devices. Fig. 3 is an end elevation of another device illustrating the association of the contiguous controlling devices. Fig. 4 is a plan view of the device shown in Fig. 3. Fig. 5 is a section through the device shown in Fig. 3. Fig. 6 is a view of the connections employed in the device shown in Figs. 2 to 5 inclusive, the covers having been removed.

Referring now to the drawings and to the illustrations of my invention shown therein, at 7 is shown the frame of an automobile horn and at 8 and 9 the front and rear parts respectively of the casing, which, when connected together form a chamber 10. An opening 11 is provided in the front 8 for the egress of sound waves and a resonator 12 is preferably mounted in this opening. A sonorous member, such as a vibratile diaphragm 13, is mounted in the chamber 10, preferably by clamping its edges between the parts 8 and 9.

I provide means for actuating the member 13 to cause it to sound a signal, and in the form shown, I have employed electrically controlled means illustrated by an electromagnet 14. The magnet 14 controls an armature 15, adapted to vibrate the member 13. I may employ means to transmit the blows from the armature to the diaphragm, and I have here illustrated an anvil 16 for this purpose. Suitable means for furnishing energy to the electromagnet is employed, and may consist of a storage battery B. One terminal of the electromagnet is connected through a conductor 17 to the vibratile armature 15, which is connected through a spring 18 to a contact 19 carried thereby. The contact 19 coöperates with the contact 20, preferably mounted upon the frame in any suitable manner. The contact 20 is connected by a conductor 21 to one terminal of the battery B. The other terminal of the battery B is connected to one of the parts of one of the contiguous controlling devices, here shown as a spring 22. The spring 22 is connected through a current modifying device 23, here shown as a non-inductive resistance, to a second spring 24 of the other contiguous controlling device. The first named contiguous controlling device is provided with a spring 25 adapted to coöperate with the spring 22, and connected through the base 26 with a spring 27 companion to the spring 24. While I have here illustrated springs, any suitable contact carrying device may be employed, and I may as shown, construct the parts 25, 26 and 27 of a single sheet of metal.

The member 26 is connected to the other terminal of the electromagnet by a conductor 28. At 29 I show means for operating the switch, composed of the contact springs 22

and 25 and at 30, means contiguous thereto for operating the switch composed of the springs 24 and 27. These means consist preferably of push buttons, being the complements of each other. In the form shown, 70 each is a section of a cylinder, so that when fitted together, they constitute a cylinder. They are best made equal in size to each other.

The operation of the device illustrated in 75 Fig. 1 is as follows:—Should it be desired to give the low tone, the edge of the thumb is pressed against the button 30, connecting the contacts 24 and 27. The button 30 may be mounted adjacent the edge of the steering wheel, so that it is natural for the driver to lay the edge of his thumb against this button first. The connection of the contact springs 24 and 27 completes a circuit through the magnet 14, the battery B and the current modifying device 23 as follows:—27—80 28—14—17—19—20—21—B—23. The magnet will then attract its armature, flexing the diaphragm and opening the contacts 19 and 20, and will continue to operate upon 90 the well known rheotome principle as long as the circuit is in this condition. However, should it be desired to give the loud signal, the thumb is either rocked so as to engage the button 29, or is pushed over to embrace 95 them both, so that the springs 22 and 25 engage, completing a circuit around the resistance 23 and shunting this resistance out, so that the energy supplied the magnet now will be greater and the blows imparted to 100 the diaphragm will be likewise greater, whereby a louder signal will be produced. It will thus be seen that the two signals may be produced without the driver detracting 105 his attention from the driving of the machine, or without his thinking. This results from the proximity of the buttons to each other, for were they mounted any distance apart, it would be necessary for him to move his hand to reach the right button and generally his eyes to direct his hand to the desired button. In my invention, however, it will never be necessary to remove the eyes from the road, since the two buttons being mounted in close relation, can be operated 110 115 to select the signal unconsciously.

In the form shown in Fig. 2 I show a casting 40 in which the buttons are mounted and which is adapted to be mounted in any suitable position, such for example as upon one of the spokes of the steering wheel. In this form, the button 30' is normally higher than the button 29' so that to produce the low signal, it is only necessary to depress the button 30', whereas to produce the loud signal, the pressure of the thumb is increased and both buttons depressed. By thus mounting the buttons contiguous to each other, I enable the driver to operate them both without moving his hand. 120 125 130

In Fig. 3 I show a bracket 41 for connecting the casing 40 to the desired part of the vehicle. In this form, the buttons 30 and 29 have their surfaces substantially flush with one another. I find that this arrangement is suitable for most contingencies, since the buttons may be operated simply by rocking the thumb or pushing it over.

In the section shown in Fig. 5, the casing 10 is illustrated as consisting of a bottom part 42 and a top 43. The top 43 has an opening 44 therein and a boss 45 formed around this opening preferably by turning up the edge of the opening. This restricts the downward motion of the buttons. The buttons are provided with an annular flange 46 which engages the under side of the top around the edge of the opening, limiting the upward movement of the buttons, which are 20 spring pressed upward by the springs 27 and 28. When the thumb is removed from the push button, and the same released, the springs 25 and 27 will of course restore the system to normal and the horn will no longer 25 be actuated.

While I have described and illustrated these particular embodiments of my invention and the particular use therefor, I do not wish to be limited to these forms or the particular use mentioned, as it will be obvious to those skilled in the art that numerous and extensive departures from the forms and details of the apparatus here shown may be made without departing from the spirit of 35 this invention.

I claim:

1. As an article of manufacture, the combination of a casing, contact springs in said casing, and complementary push buttons 40 each consisting of a segment of a cylinder mounted contiguous to each other in said casing and controlling said contact springs, said buttons mutually sustaining each other.

2. As an article of manufacture, the combination of a casing, a plurality of contact springs mounted in said casing, a plurality of complementary push buttons, each consisting of a segment approximating a half cylinder, mounted contiguous to each other 50 in said casing to reciprocate therein and controlling said contact springs, said buttons mutually sustaining each other.

3. As an article of manufacture, the combination of a casing having an opening 55 therein, a plurality of contact springs in said casing, complementary push buttons each

consisting of a segment of a cylinder mounted in said casing and projecting through the opening, said push buttons having flanges adapted to engage the edge of the opening 60 in the casing, said push buttons controlling said contact springs.

4. As an article of manufacture, the combination of a casing having an opening therein, a boss around the edge of said opening, a plurality of contacts in said casing, complementary push buttons mounted in the opening in said casing and having their sides engage the boss about the edges, said push buttons engaging the under side of the edge 70 of the opening when said push buttons are in normal position, such push buttons controlling said contacts.

5. As an article of manufacture, the combination of a casing having an opening 75 therein, contact springs mounted in said casing and complementary push buttons controlling said springs, said buttons mounted in said casing and projecting through the opening therein, one of said buttons being 80 longer than the other and when in normal position having its upper surface above the upper surface of the shorter button, said buttons being depressed simultaneously.

6. As an article of manufacture, the combination of a casing having an opening therein, a boss around the edge of said opening, a plurality of contacts in said casing, a pair of push buttons mounted in said casing and projecting through the opening, each 90 button being the complement of the other and the two together constituting a substantially cylindrical device, the outer cylindrical surface engaging said boss and the buttons mutually sustaining each other through 95 engagement at the inner surfaces, one of said buttons being longer than the other, means holding the buttons in normal position with the upper surface of the shorter button below the upper surface of the longer button, 100 said means permitting the depression of the buttons separately or together when the longer is depressed until the upper surfaces are substantially flush, and electrical contacts controlled by said buttons.

In testimony whereof, I affix my signature in the presence of two witnesses.

RAY H. MANSON.
